Attorney.

UNITED STATES PATENT OFFICE

HENRY OESTE, OF PITTSBURGH, PENNSYLVANIA

RACE TIMING APPARATUS

Application filed August 7, 1930. Serial No. 473,542.

My invention relates to race timing apparatus, and more particularly, in pigeon racing, to apparatus for accurately timing the homing flight of racing pigeons.

5 In pigeon racing, it is usual to have pigeons registered in a race from widely separated points, and the flight of each pigeon is directly to its home quarters. Although a pigeon race may be started at a central 10 point, the end of the race for each entrant is its home quarters, thus making it inconvenient to have an official timer stationed at each of the quarters of the racing pigeons to officially note the time of arrival of each 15 pigeon.

One object of my invention is to provide timing apparatus that the owners of the pigeons may have officially registered and which may be used to indicate the time of arrival 20 of the homing pigeons.

Another object of my invention is to provide a timing apparatus of such form that improper manipulation or tampering with the apparatus will be apparent, and will result in the disqualification of the owner and 25 the pigeon.

Another object of my invention is to provide timing apparatus of simplified construction, and which will be reliable in operation.

30 Further objects of my invention will be apparent from the detailed description which follows, taken in conjunction with the drawing, which illustrates one embodiment of the invention, and wherein:

35 Figure 1 is a face view of the timing apparatus, a portion of the cover thereof being broken away to more clearly show the structure, and portions of the structure being cut away to show the details; Fig. 2 is a view taken on the line II—II of Fig. 1; Fig. 3 is a vertical sectional elevational view of one of the clock-actuated elements of Figs. 1 and 2; Fig. 4 is a view taken on the line IV—IV of Fig. 3 with the parts moved to 40 time-indicating position; and Fig. 5 is an elevational face view of Fig. 3 with the mechanism thereof in actuated position.

45 In practising my invention, I provide a time indicating clock mechanism having a usual type clock or watch movement 6 which

is securely clamped between plates 7 and 8, as by means of screws and spacer pins 9. A spacer ring 10 is positioned between the plate 8 and the movement 6 to fully enclose and protect the same from dust or dirt. A 55 cylindrical casing or receptacle 11, having a bottom plate 12 set inwardly from one end thereof, is rotatably mounted on the plate 8. The plate 8 is provided with an outwardly projecting pin or shaft 13 which extends through a central perforation in the plate 12 for rotatably supporting the casing 11. A ratchet wheel 14 is non-rotatably mounted on the outer end of the shaft 13 and is secured thereon by means of a screw 15. A 60 spring-pressed pawl 16 is pivotally mounted on the plate 12 for cooperative engagement with the teeth of the ratchet wheel 14, and serves to prevent rotative movement of the casing in one direction for a purpose as hereinafter described. 65

The clock mechanism 6 is provided with a balance wheel 17 which is normally held against movement by a yieldable stop member 18 which is secured to an arm 19. The 70 stop member 18 projects downwardly through a suitable slot in the plate 8 and engages the periphery of the balance wheel 17 shown in Figs. 1 and 3. The arm 19 is pivotally secured at one end to the plate 8 and extends substantially diametrically across the casing 11 with the free end of the arm 19 in abutting engagement with the side wall of the casing 11. The arm 19 is yieldably 75 secured at one end to the plate 8 and extends substantially diametrically across the casing 11 with the free end of the arm 19 in abutting engagement with the side wall of the casing 11. The arm 19 is yieldably 80 secured at one end to the plate 8 and extends substantially diametrically across the casing 11 with the free end of the arm 19 in abutting engagement with the side wall of the casing 11. The arm 19 is yieldably 85 secured at one end to the plate 8 and extends substantially diametrically across the casing 11 with the free end of the arm 19 in abutting engagement with the side wall of the casing 11. The arm 19 is yieldably 90 secured at one end to the plate 8 and extends substantially diametrically across the casing 11 with the free end of the arm 19 in abutting engagement with the side wall of the casing 11. The arm 19 is yieldably 95 secured at one end to the plate 8 and extends substantially diametrically across the casing 11 with the free end of the arm 19 in abutting engagement with the side wall of the casing 11. The arm 19 is yieldably 100 secured at one end to the plate 8 and extends substantially diametrically across the casing 11 with the free end of the arm 19 in abutting engagement with the side wall of the casing 11.

The casing 11 is provided with a cap or end plate 22 which is provided with an outwardly projecting knob 23 by means of which the casing may be rotated. The casing is divided into compartments by a plate or wall member 24. One of the compartments con-

tains the pawl and ratchet mechanism as described, while the other compartment is adapted to receive an identification element or ring (not shown) which may be deposited therein through an opening 25 in the cap 22. Such an identification ring may be a rubber band which may be placed around a leg of a racing pigeon, so that, at the end of its flight, the ring may be removed and inserted into the compartment of the casing through the opening 25, at which time the casing may be rotated to release the balance wheel, whereby the timing mechanism 6 is permitted to operate.

15 The mechanism thus far described forms a timing unit which serves to register the time of arrival of one bird. One of such units is necessary for each bird entered in a race, the birds and the units therefore being officially registered.

20 A casing or container 26 is provided for the units, and the casing may be of such size as to accommodate one or more such units, as is desired, a casing for housing two timing units being illustrated. The casing 26 comprises a flanged bottom plate 27 and a cover having side walls 28 and a top wall 29. The bottom plate is provided with a centrally positioned post 30 that has a reduced screw-threaded outer end which projects through an opening in the top wall 29, and on which a knurled nut 31 is threaded to clamp the cover to the bottom plate. The nut 31 may be officially sealed in any desired manner, as by means of a seal 33 extending through a transverse perforation in the nut and the end of the post, whereby unauthorized opening of the casing will be immediately apparent.

25 A timing unit is positioned on the bottom plate 27 at one side of the post 30, and the plate 7 of such unit is provided with spaced pins 32 which extend into correspondingly spaced perforations in the bottom plate to maintain the unit against sliding movements in the casing. Another such unit may be similarly positioned at the opposite side of the post 30, if desired. The top wall 29 of the cover is provided with an opening 34 through which the knob 23 of the cylindrical casing of the unit extends, so that the mechanism 6 may be operated from the exterior of the casing 26. As shown in Fig. 1, the top wall 29 is provided with a passageway 35 with which the opening 25 in the rotatable casing 11 registers when the apparatus is officially adjusted by the judges of a race, and in this position the identification ring may be inserted into the casing 11 as previously described.

30 A stop lug 36 is secured to the cylindrical casing 11 and engages the post 30 when the casing is rotated, to limit rotative movement thereof to a predetermined degree so that the slot 21 will be accurately positioned to permit movement of the arm 19 to release the bal-

55

ance wheel, as hereinbefore described, this position of the apparatus being shown in Fig. 5. Since the pawl and ratchet mechanism prevents counter-rotative movement of the casing 11, the timing apparatus cannot be returned to its initial position until the seal 33 is broken and the unit removed from the casing 26.

A further feature of my invention is the provision of protecting means for shielding the clock mechanism against any attempts to influence the action of the mechanism by the use of magnetism. It is well known that the balance wheel and the hair-spring of a clock mechanism may be magnetized and the accuracy of the timepiece impaired thereby. However, I prefer to form the container or casing 26 of a non-magnetic material, and to completely enclose the same exteriorly by a shell or shield 37 of a material that is readily susceptible to the action of a magnetic field, thus forming a kind of screen protecting the inside of the casing from the influence of an external field. The shield 37 forms a closed magnetic circuit of low reluctance which effectively protects the enclosed mechanism, while the non-magnetic casing 26 interposed between the outer casing and the mechanism, protects the mechanism, so that the induction of a magnetic field is greatly decreased.

60 Briefly, the functioning of the apparatus to time a race is as follows:

A timing apparatus is registered for timing the flight of a particular pigeon. An official of the race will set the indicating hands of the clock mechanism to indicate any predetermined time, for example 12 o'clock 60 seconds. The casing 11 is then rotated to move the arm 19 to hold the balance wheel against operation, and the unit is positioned and sealed in the casing 26 with the passageway 35 and the opening 25 in registry, as shown in Fig. 1. The sealed apparatus is returned to the owner, to be on hand at the end of the flight of the pigeon.

When the pigeon is released for its homing flight, the time of release is noted officially, for example 12 o'clock. As soon as the pigeon reaches its quarters it is caught and the identification ring carried thereby is inserted through the openings 25 and 35 of the timing apparatus, and the receptacle 11 is rotated by means of the knob 23, until the stop lug 36 engages the post 30, the opening 25 being moved out of registry with the passageway 35. The slot 21 in the receptacle 11 is brought into position to permit movement of the arm 19 thereby releasing the balance wheel 17 and the watch movement operates to register the passage of time.

The timing apparatus is returned to the race official, who removes the timing mechanism, and compares the time indicated thereby with the official timepiece. The difference between the official time and the time

indicated by the timing apparatus being the time required for the homing flight of the pigeon. For example, if the timing mechanism indicates the elapse of one hour, or 1 o'clock, and the official timepiece indicates the elapse of three hours from the start of the race, or 3 o'clock, the flying time of the pigeon would be two hours.

In this manner, the flying time of each **10** pigeon may be accurately determined, regardless of the time required for the return of the timing apparatus to the race official. Further, it will be seen that the timing apparatus must pass official inspection, otherwise **15** the owner and his pigeon will be disqualified, thus eliminating the possibility of the apparatus being tampered with while being away from the race official.

I claim as my invention:—
20 1. Race timing apparatus comprising a casing, a clock mechanism having a balance wheel, and insertible in the casing, a lever movable into and out of engagement with said balance wheel, a rotatable member supported on said mechanism and operable exteriorly of the casing for moving said lever, and a pawl and ratchet device arranged between said mechanism and said member and operative to prevent rotative movement of **25** said member in one direction.

30 2. Race timing apparatus comprising a casing, a clock mechanism having a balance wheel, and insertible in the casing, a lever mounted on said mechanism normally positioned in engagement with said balance wheel and movable away therefrom to permit actuation of the said mechanism, a rotatable member supported on said mechanism and operable from exteriorly of the casing for **35** moving said lever, stop means arranged between said member and the casing and operative to permit only a limited rotative movement of said member in one direction, and means engaging said member for preventing **40** rotative movement thereof in the opposite direction.

45 3. Timing apparatus comprising a casing, a clock mechanism having a balance wheel, and insertible in the casing, a lever mounted on said mechanism and movable into and out of engagement with said balance wheel, a receptacle rotatably mounted on said mechanism and operable from exteriorly of the casing for moving said lever, a pawl and ratchet device connected to said receptacle for preventing rotative movement thereof in one direction, and a stop lug secured to said receptacle in position to engage said casing for **50** limiting movement of the receptacle in the other direction.

In testimony whereof I, the said HENRY OESTE, have hereunto set my hand.

HENRY OESTE.
